The ornamental design for a holder for single beverage container, as shown and described.

DESCRIPTION

FIG. 1 is a perspective view of a holder for single beverage container, showing my design;
FIG. 2 is a right side elevation view;
FIG. 3 is a front elevation view;
FIG. 4 is a top view; and,
FIG. 5 is a bottom view.

The left side elevation view is a mirror image of the right as seen in FIG. 2. The rear elevation view is a mirror image of the front elevation view as seen in FIG. 3.
